RADIATOR ENCLOSURE

Thomas O. Marini, Camden, N. J., assignor to
Marver Metal Mfg. Co., a corporation of Delaware

Application October 11, 1946, Serial No. 702,737

7 Claims. (Cl. 237—79)

1

The invention relates to radiator enclosures or covers which completely house the radiator, and more particularly to an enclosure of the knock-down type.

Because of the bulk of a radiator enclosure, it is common practice to construct it of parts readily assembled. This construction effects economies in packaging, storage space, shipment, etc. However, it has certain disadvantages in that at the place of installation, unskilled labor is often employed which frequently introduces an assembly problem, particularly if tools are required.

It is an object of the present invention to provide a radiator enclosure of the knock-down type, characterized by simplicity of construction, ease of assembly with respect to time and tools required, etc.

Another object is the provision of a radiator enclosure having rounded corners at the front and forming an interlocking joint so that when the construction is assembled, a rugged enclosure is obtained.

A special object of the invention is the provision of a bracket device that may be formed as a unit by a dye operation and pre-fabricated as part of an end section adapted to form an interlocking joint with a wall section by merely bringing the interlocking portions into engagement without the necessity of tools.

Other objects and advantages of the invention will become apparent as the description proceeds.

For a full and more complete understanding of the invention, reference may be had to the following description and accompanying drawings, wherein:

Figure 1 is a perspective view of the assembled radiator enclosure;

Figure 2 is a top plan view, with parts broken away, of the enclosure;

Figure 3 is a vertical section taken on the line 3—3 of Figure 2;

Figure 4 is a fragmentary horizontal sectional view, taken along the line 4—4 of Figure 3; and

Figure 5 is a fragmentary view in elevation, showing a corner rest member for the top of the enclosure.

The radiator enclosure herein contemplated may be formed of separate parts made of sheet steel or other suitable material. The enclosure comprises a top 1, a front and rear wall 2 and 3, respectively, and end panels 4 and 5. These parts are normally disassembled to save storage and shipping space. However, at the place of installation, they may be readily assembled by an un-

2

skilled person and with the use of a few simple tools.

The front wall 2 may comprise a frame formed by top and bottom rails 7 and 8 respectively, which are secured at their ends to angle pieces 9 and 10. A grill section 6 may be suitably secured to this frame by spot welding or the like. It will be noted that the outside edges of the rails 7 and 8 and angle pieces 9 and 10 are provided with flanges bent at an angle of substantially ninety degrees. Attention may be directed to the fact that the height of the end panels 4 and 5 is somewhat greater than the width of the walls 2 and 3, so that said walls may be supported from said panels free from the floor, which arrangement will become apparent as the description proceeds.

The end panels 4 and 5 have rounded corners 11 and 12 respectively, and each is provided with a bracket member, indicated generally by the reference character 13. This bracket member may be formed of a single piece of sheet metal having a body section 14, which terminates in side portions 15 and 16, bent at an obtuse angle to the body section 14. The bracket member 13 is designed to fit into the rounded corners 11 and 12 of the end panels 4 and 5, and the angularity of the side portions 15 and 16, with respect to the body portion 14 roughly determines the spacing of the bracket from said corners. That is to say, the less obtuse the angle of displacement of the side portions 15 and 16 to the body section 14, the closer the bracket may be placed with respect to the rounded corners, and vice versa, the more obtuse this angle, the further away will the bracket be located. Therefore, the geometry and dimensions of the bracket elements are important factors in designing the bracket from the standpoint of securing optimum results.

It will be noted that the body section 14 of the bracket 13 may be regarded as a strut member joining the side portions 15 and 16. The side portion 16 is of greater length than the side portion 15, inasmuch as the edge thereof is provided with a flange 17 reversely bent upon itself to form a groove 18, which arrangement constitutes a clip 20 adapted to receive the flange 19 of the pieces 9 and 10 of the front wall 2.

It will be seen that the construction of the bracket 13 readily lends itself to a die stamping operation, and the bracket may be suitably welded to the end panels as a pre-fabricating step. From that standpoint, no assembly of the bracket is required as part of the installation of the radiator enclosure. The location of the bracket

13 within the rounded corners of the several end panels is important in that the bracket is so mounted that the edge of the flange 21, extending laterally from the front wall 2, functions as a support therefor (see Figure 3). This will be explained more fully presently.

It will be noted that the spacing of the clip 20, formed by bending the flange 17 upon itself, is a substantial distance from the front edge of each of the panels 4 and 5, thus providing an extension which produces an over-lapping of the adjacent edges when the flange 19 of the front wall is inserted into the groove of the clip 20. As an expedient to insure a snug fit of the flange 19 within the clip 20, the free or projecting edges of the panels are each provided with a rolled-over portion forming a bead 21 which is designed to function as a pivotal point in holding the front wall 2 parallel to the rear wall 3 when the front wall is locked into engagement with the clips 20.

Referring particularly to Figures 2 and 5, it will be noted that the rounded corners 11 and 12 of the end panels 4 and 5 are each provided with a rest plate 23. The plates 23 project outwardly from said corners and are shaped to permit the fitting of the edge flange portion 24 of the top 1 thereover, when the top is in place. By having the rest plates 23 project over the rounded corner of the end panels, said plates constitute a support for the top 1. As is customary, the top 1 may have a filler of sheet asbestos (not shown) held in place by any suitable retaining means, such as lugs or clips.

In the assembly of the radiator enclosure, one of the end panels may be set up vertically and an end of the wall section 2 locked onto the bracket 13 by inserting the flange 19 into engagement with the groove 18. This may be effected by slightly twisting or tilting the wall 2 inwardly, as shown by the dotted lines in Figure 4. Upon insertion of the flange 19 into the groove 18, the wall 2 is moved forwardly and the flange thus becomes tightly clamped in the clip 20, forming an interlocking joint. The outward movement of the wall 2 is limited by its engagement with the beaded edge 21. In a similar manner, the other end panel is locked to the opposite end of the wall 2. With the two end panels now hinged to the front wall 2 by interlocking engagement therewith, the rear panel 3 may be attached in place. Any simple form of fastening means may be used for this purpose, and in the drawing I have indicated a bolt construction comprising upper and lower bolts 25 and 26 held in place by nuts 27 and 28. The bolts pass through apertures 29 on the marginal edge of the flange 30, formed on the end panels 4 and 5. Registering apertures 31 are formed in the rear wall 3, and as an expedient to take care of slight variations in construction, these apertures may be oblong so as to permit more accurate alignment of the end panels with the rear wall.

From the foregoing description, it will be appreciated that the only tool needed in the assembly of the radiator enclosure is a screw driver for tightening the bolts 25 and 26. Due to the simplicity of construction, no skill whatever is required on the part of the person making the assembly, and it is obvious that it may be done within a very short time.

While certain preferred embodiments of the invention are hereinbefore set forth, it is to be clearly understood that the invention is not to be limited to the exact construction illustrated and described because various modifications of the

details may be provided in putting the invention into practice within the purview of the appended claims.

What is claimed is:

- 5 1. A radiator enclosure of the character described, including in combination, an end panel having a corner formed on a radius, means for securing said panel to a front wall, said means comprising a bracket member having a body section provided with side portions bent at an obtuse angle thereto, the angularity of the side portions with respect to the body section being such that the body section forms a strut element for said side portions, one of said side portions being provided with a clip formed by reversely bending the edge thereof upon itself to provide a groove, a flange projecting inwardly from the vertical edge of said front wall, the relation of said flange to said groove being such that when they are brought into engagement they form an interlocking joint for holding the wall and the panel firmly together.
- 10 2. In a radiator enclosure of the class described, the combination with front and rear walls, of an end construction comprising a panel having a front section and a side section joined by a corner formed on a radius, the vertical edge of said front section terminating in a bead, interlocking elements disposed between said rear flange and said rear wall, a bracket member having a body section provided with side portions bent at an obtuse angle thereto, the angularity of the side portions with respect to the body section being such that the body section forms a strut element for said side portions, said bracket being secured within the corner of the end panel formed on a radius, said bracket and panel constituting a pre-fabricated unit, a clip formed along the vertical edge region of said bracket, said clip being adapted to receive a flange projecting inwardly from the vertical edge region of the front wall, the spacing of said clip with respect to the adjacent vertical edge of said panel being such that the opposing edges of the panel and wall over-lap, the arrangement of said clip and flange being such that they interlock when the flange is inserted into the clip by an inward and outward movement of the wall, using the clip and bead as pivotal points for said movements.
- 15 3. In a radiator enclosure of the character described, the combination of a front and an end panel having a corner formed on a radius and being provided with a bracket member adapted to fit within said corner, said bracket member comprising a body section having angularly disposed edge portions, a clip formed along the vertical edge region of one of said portions, said clip being adapted to receive a flange projecting inwardly from the vertical edge region of the front wall, said clip and flange when in engagement constituting an interlocking joint for holding the front wall and end panel together.
- 20 4. A radiator enclosure comprising front and rear walls joined by interlocking end panels, each of said end panels having a corner formed along a curve and being provided with a bracket member adapted to fit within said corner, said bracket member comprising a body section having angularly disposed edge portions, one of said edge portions having a flange bent to form a groove adapted to receive a flange projecting from the front wall, said flange and groove when in engagement constituting an interlocking joint for holding together the front wall and the respective end panels.

- 70

5. A radiator enclosure of the character described, including in combination, prefabricated elements comprising an end panel having a corner formed along a curve, means for securing said panel to a front wall, said means comprising a bracket member having a body section provided with a side portion bent at an obtuse angle thereto, the angularity of the side portion with respect to the body section being such that the body section forms a strut element for said side portion; a clip comprising a groove; a flange adapted to be brought into engagement with said clip and to be interlocked therewith; said flange projecting from one of said elements and said clip projecting from another of said elements; the relation of said flange to said groove being such that when they are brought into engagement they form an interlocking joint for holding the wall and the panel together.

6. A radiator enclosure of the character described, including in combination, a front wall, and an end panel having a corner formed along a curve, means for securing said panel to said front wall, said means comprising a bracket member having a body section provided with a side portion projecting at an obtuse angle thereto, said body section forming a strut element for said side portion, said bracket being secured to said end panel in such a manner as to subtend the corner thereof, the positioning of said bracket with respect to said corner being such that an upper edge portion of the bracket supports the front wall substantially flush with the top edge of the panel and holds the bottom of said wall free from the floor, interlocking elements comprising a clip and a flange, one of said elements being disposed on

said bracket, and the other of said elements being disposed on said front wall, said clip being adapted to receive said flange in a manner to interlock therewith when the flange is inserted into the clip by a movement of the wall, using the clip as a pivotal point for said movement.

7. A radiator enclosure of the character described, including in combination, a top, a front wall, and end panels for supporting said wall, all 10 of said parts being prefabricated, the end panels comprising a corner formed along a curve, a bracket member secured to at least one of said end panels in a manner to subtend said corner thereof, interlocking elements comprising a clip 15 and a flange, one of said elements being disposed on said bracket, and the other of said elements being disposed on said front wall, said flange being adapted to provide an interlocking joint with said clip, and said front wall and end panel being locked together by a relative twisting movement of said wall and end, and a rest plate disposed at the top of an end panel and positioned over the curved portion thereof, the top section having its outer corners fitted over said plate.
